UNITED STATES PATENT OFFICE.

JOSEPH H. FINK, OF NEW YORK, N. Y.

DESIGN FOR A FINGER-RING.

SPECIFICATION forming part of Design No. 21,926, dated October 25, 1892.

Application filed September 16, 1892. Serial No. 446,101. Term of patent 3½ years.

To all whom it may concern:

Be it known that I, JOSEPH H. FINK, of New York city, New York, have invented and produced a new and original Design for Finger-Rings, of which the following is a specification, reference being had to the accompanying drawing, which represents a perspective view of a finger-ring provided with my design.

The leading feature of my design consists of a picture of Columbus placed between two flags and between a steering-wheel and an anchor.

a represents a finger-ring, upon which there

is engraved the head *b* of Columbus. To 15 either side of the head *b* there is shown an American flag *c*, which is represented as being folded around the ring *a*. A steering-wheel *d* and an anchor *e* are shown to the right and left of the head *b*. 20

What I claim is—

The design for a finger-ring, substantially as herein shown and described.

JOSEPH H. FINK.
